UNITED STATES PATENT OFFICE.

AUSTIN A. GREEN, OF BRUSHTON, NEW YORK.

THILL-COUPING.

1,118,486.

Specification of Letters Patent. Patented Nov. 24, 1914.

Application filed May 20, 1914. Serial No. 839,804.

To all whom it may concern:

Be it known that I, AUSTIN A. GREEN, a citizen of the United States, residing at Brushton, in the county of Franklin and State of New York, have invented a new and useful Thill-Coupling; and I do hereby declare the following to be a full, clear, and exact description of the invention, such as will enable others skilled in the art to which it appertains to make and use the same.

This invention relates to an improved thill coupling.

An object of the invention is to provide an improved coupling between the thill or the rear curved portion of a shaft and the forward axle comprising certain improved features of construction.

In practical fields the minor details may be subjected to alterations, falling within the scope of what is claimed.

The invention comprises further features and combination of parts, as hereinafter set forth, shown in the drawings and claimed.

In the drawings:—Figure 1 is a view in perspective of the thill coupling. Fig. 2 is a sectional view through Fig. 1. Fig. 3 is a vertical sectional view. Fig. 4 is a view showing the various parts of the coupling in perspective and disassembled.

Referring to the drawing, 1 designates the usual axle and 2 a conventional form of bolster, while 3 denotes the clips, and 4 the plate to receive the threaded shanks of the clips, on which shanks suitable nuts 5 are arranged to hold the clips in place, thereby clamping the axle and the bolster together.

One of the clips 3 is provided with laterally extending lugs 6 having apertures 7, in the wall of each of which a notch 8 is constructed. These notches 8 are a little out of alinement or registration and extend in a direction toward the clips. The thill 9 has secured upon its under surface a plate 10, and on its upper surface a second plate 11, bolts 12 extending through the plate 11, the thill, and the plate 10 and provided with nuts 13, to hold said parts together.

The plate 10 at one end terminates in a cylindrical sleeve or collar 14, the inner wall 50 of the bore 15 of which is provided with a groove 16 which extends at an angle to the length of the bore, and one end of the groove registers with one of the notches 8, while the other end registers with the opposite notch.

A pin 18 is designed to pass through said apertures and through the bore of the cy-

lindrical sleeve or collar, so as to connect the lugs of one of the clips and the plate 10. One end of this pin has an angular portion 19. Extending slightly angularly out of alinement with the pin is an elongated rib 20. When inserting the pin the rib passes through the notch 8 of one of the apertures and assumes a position in the groove of the sleeve or collar, in which case the pin will then rotate with the sleeve or collar when the thill or rear portion of the shaft is moved to a position shown in Fig. 1. This rib is substantially of a length corresponding to the length of the groove, therefore, 60 one end of the rib terminates a short distance from the angled end of the pin, so as to permit the thickness of one of the lugs of one of the clips to pass between the angled end and the end of the rib. The other end 70 portion of the pin is provided with a lug 21 which is alined with the rib. This lug, when inserting the pin, passes through the notches of said apertures and through the groove and assumes a position adjacent the outer 75 face of the lug next to the other end of the sleeve or collar opposite and beyond the angled end of the pin, so that when the thill is moved to a position shown in Fig. 1, said lug assumes a position out of registration 80 with the notch, in which case endwise movement of the pin is prevented. The lug 21 is not only alined with the rib, but is spaced apart from one end thereof so as to permit the thickness of one of the lugs to pass between the lug on the pin and the end of the rib. A corner 22 of the groove engages a slight longitudinal groove 23 of the pin, which groove 23 is adjacent to and parallel 90 to said rib. The rib comprises a pin, which is arranged adjacent to the pivot pin and has its angled ends 24 wedged in recesses 25 of the pivot pin, so as to hold the rib pin in place. It will be observed that when the thill is arranged as in Fig. 1, the rib is out 95 of alinement with said notches, as is also the lug on the end of the pivot pin, thereby holding the parts connected.

The invention having been set forth, what is claimed as new and useful is:—

A thill coupling comprising a clip having a pair of laterally extending lugs provided with apertures in registration with each other, a thill plate having a cylindrical hollow sleeve upon the inner circumference of 100 the bore of which an elongated groove is provided, said apertures having notches

upon their inner circumferences, a pivot pin having an angular end at one end, and a radial lug at the other adapted to pass through said notches and said groove, said pivot pin having an elongated rib spaced apart between said lug and said angular end adapted to be received in said groove thereby rotating with the sleeve or collar, said lug extending from the pivot pin in a direction at 10 right angles to the angular end, so that when the pivot pin is rotated with the sleeve, said lug will assume a position out of alinement with one of the notches, said groove and said notches being in registration when first 15 inserting the pivot pin and extending at an

angle to the pivot pin, said rib and said lug correspondingly being non-axially arranged with relation to the pivot pin, thereby rendering it difficult for the pivot pin to become displaced in case the rib and the lug are in registration with said notches, and a groove in the pivot pin adjacent the rib to receive a corner of the groove. 20

In testimony whereof I have signed my name to this specification in the presence of 25 two subscribing witnesses.

AUSTIN A. GREEN.
